CLAIM

The ornamental design for a nozzle for hairdryer, as shown.

DESCRIPTION

FIG. 1 is a perspective view showing a nozzle for a hairdryer design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The portions of the nozzle for hairdryer shown in broken lines are included for the purpose of illustration unclaimed portions of the nozzle for hairdryer and form no part of the claimed design.
